UNITED STATES PATENT OFFICE.

MICHAEL O'BRIEN, OF CHICAGO, ILLINOIS, ASSIGNOR TO CHICAGO CITY RAILWAY COMPANY, OF CHICAGO, ILLINOIS, A CORPORATION OF ILLINOIS.

BRAKE-OPERATING DEVICE.

SPECIFICATION forming part of Letters Patent No. 741,160, dated October 13, 1903.

Application filed March 25, 1901. Serial No. 52,681. (No model.)

To all whom it may concern:

Be it known that I, MICHAEL O'BRIEN, a citizen of the United States, residing at Chicago, in the county of Cook and State of Illinois, have invented a certain new and useful Improvement in Brake-Operating Devices, of which the following is a specification.

My invention relates to devices for operating brake mechanisms, and has for its object to provide a new and improved device of this description particularly adapted to be used in connection with street-cars.

My invention is illustrated in the accompanying drawings, wherein—

15 Figure 1 is a plan view with the roof removed, showing the platform of a street-car supplied with my device for operating the brakes. Fig. 2 is a view in part section, showing the connection between the operating-handle and the brake-rod. Fig. 3 is a view of the end of the operating-handle as seen from beneath. Fig. 4 is a plan view of the construction shown in Fig. 2 with the operating-handle and associated clutch-piece removed. 25 Fig. 5 is a view as seen from below of the clutch-piece associated with the operating-handle. Fig. 6 is a section on line 6-6, Fig. 3.

Like letters refer to like parts throughout the several figures.

30 My invention is particularly adapted to be used where the sweep or movement of the operating-handle is for some reason limited.

In Fig. 1 I have illustrated my invention as applied to a street-car having the platform 35 inclosed, so as to provide a protection for the operator or motorman. With such a construction the ordinary brake-rod would have to be placed near the middle of the platform or at a distance from the end of the car 40 greater than the length of the handle, so that it could be rotated. When in this position, it is out of the reach of the operator and also takes up too much space and is inconvenient and undesirable in many ways. When my 45 invention is used, the brake-rod can be placed very close to the end of the car, as shown in Fig. 1, and all the advantages derived from such position may be obtained.

In carrying out my invention I provide the 50 operating-handle A, said handle being movably associated with the brake-rod in any de-

sired manner, so it can be turned without moving said rod. As herein shown, the brake-rod B is provided with a groove B', and one or more pins, set-screws, projections, or the like 55 A' are connected with the operating-handle, so as to project into this groove. This holds the handle from being removed and yet gives a free relative movement between the handle and the rod. The handle is provided with 60 an enlarged cup-shaped or receptacled end A². This end is provided with the space or hollow portion A³ and the grooves or notches A⁴. A movable clutch member or piece C is inserted in the space or hollow portion A³ 65 and is provided with the projections or wings C', which fit into the grooves or depressions A⁴ in the handle. The handle is preferably provided with the projecting guide-pieces A⁵ on each side of the clutch member C. At 70 attached to the brake-rod in any desired manner is a clutch member or piece D, adapted to engage the movable clutch member C. As herein shown, the clutch member D is provided with the non-circular part D'. The 75 brake-rod is threaded, and the part D' is provided with a thread which engages the thread on the rod, thus holding the clutch member in place. The clutch member C is free to move in the handle A, but is normally forced 80 toward the clutch member D by gravitation or some other means, such as the spring B². The guide-pieces A⁵ preferably project downwardly, so as to partially inclose the clutch member D. The teeth of the two 85 clutch members are so shaped that when the handle is moved in one direction they engage, so as to cause the brake-rod to rotate, and when the handle is moved in the other direction they automatically become disengaged, so that the handle moves back free 90 from the brake-rod, the brake-rod being held by any desired mechanism, such as the dog E. The brake-rod is connected to the brakes, which may be of any desired description, by 95 the chain or other device D². A releasing device is provided for automatically releasing the brakes. As herein shown, the bracket F, in which the brake-rod is mounted, is provided with the inclined face or faces F'. The 100 projections or wings C' on the clutch member C are also preferably provided with in-

clined faces C². These several inclined faces are arranged so that they are normally out of engagement when the brake is being operated. When it is desired to release the brake, 5 the handle is moved so as to bring these inclined faces into engagement. The inclined faces on the clutch member C then ride upon the inclined faces F' and cause said clutch member to be raised, so as to become disengaged from the clutch member D. The brake-rod being then released rotates so as to release the brakes. I prefer to arrange these inclined faces so that they come into engagement when the operating-handle is moved to 10 its extreme limit in proximity to the wall—that is, to its inoperative position. I also prefer to provide a limiting device which prevents the handle from striking the wall, so as to mar it, and which also prevents the 15 hand of the operator from being injured. Any desired means for this purpose may be used. As herein shown, the bracket F is provided with a lug G and the handle is provided with a lug H, the two lugs adapted to 20 engage, as shown in Fig. 2, before the handle 25 strikes the wall.

It will thus be seen that in operating the brake the operator moves the handle from the wall and then moves it back and forth 30 through an arc until the brake is properly set, the two clutch members becoming alternately engaged and disengaged. When it is desired to release the brake, the operator simply moves the handle to its inoperative 35 position, whereupon the clutch member C is lifted and the brake-rod released.

I claim—

1. A brake-operating device, comprising an operating-handle, a movable clutch member 40 mounted thereon, a second clutch member connected with a movable part which actuates the brakes, both clutch members mounted about the same axis and a releasing device adapted to act upon the clutch member 45 mounted on said handle so as to move it with relation to said handle and release or disengage the two clutch members when the handle is moved to a predetermined position.

2. A brake-operating device, comprising an operating-handle provided with an enlarged 50 receptacle end, a loose clutch member movably mounted in said receptacle end so as to rotate with the handle, but free to move to and fro, a second clutch member connected 55 with a movable part which actuates the brakes, the two clutch members adapted to normally engage, and a releasing device adapted to move said first clutch member with relation to said handle to release or disengage the clutch members when the operating-handle is moved to its inoperative position.

3. A device for operating brakes on vehicles, comprising an operating-handle having an enlarged or receptacle end, a movable 65 clutch member loosely mounted in said receptacle end so as to rotate with the handle, a second opposed clutch member connected

with the movable part which actuates the brakes, the two clutch members adapted to normally engage, an engaging part on the 70 movable clutch member, a coacting engaging part so positioned that when engaged by the part on the movable clutch member said member will be moved so as to be released from the opposed clutch member and release the 75 brakes.

4. A device for operating brakes on vehicles, comprising an operating-handle provided with an enlarged or receptacle end, a clutch member provided with projecting wings and 80 loosely mounted in said end so as to rotate with the handle, but free to move with relation to the handle, a second opposed clutch member connected with the brake-rod, a stationary part or bracket in which the brake-rod is mounted, said part provided with one or more engaging parts adapted to engage the 85 wing or wings on the movable clutch member and move said clutch member so as to release it from the opposed clutch member 90 when the handle is moved to a predetermined position.

5. A device for operating brakes on vehicles, comprising an operating-handle provided with an enlarged or receptacle end, a clutch 95 member provided with projecting wings having beveled faces and loosely mounted in said end so as to rotate with the handle, but free to move with relation to the handle, a second opposed clutch member connected with the 100 brake-rod, a stationary part or bracket in which the brake-rod is mounted, said part provided with one or more engaging parts, having inclined faces adapted to engage the 105 inclined faces of the wings associated with the movable clutch member and move said clutch member so as to release it from the opposed clutch member when the handle is moved to a predetermined position.

6. A device for operating brakes on vehicles, comprising an operating-handle provided at one end with a hollow portion, two grooves or depressions connected with said hollow portion, a movable clutch member loosely mounted in said hollow portion and provided 110 with wings which fit into said grooves or depressions, said wings having inclined faces, a second opposed clutch member connected with the brake-rod, a spring normally tending to force the two clutch members together, a stationary part or bracket, which acts as a bearing for the brake-rod and provided with one or more inclined faces adapted to engage the inclined faces on the wings of the 115 movable clutch member when the handle is moved to a predetermined position, so as to lift said movable clutch member and release the brake-rod.

7. A brake-operating device, comprising an operating-handle, two clutch members associated therewith each having a series of opposed projecting engaging parts or teeth, one 120 rotating with the handle and the other with the part which actuates the brakes, one of

said clutch members being movable in a direction to disconnect said members, and a releasing device associated with said movable clutch member and adapted to move it, to 5 release or disengage the two clutch members when the handle is moved to a predetermined position.

8. A brake-operating device, comprising an operating-handle, a brake-rod, two clutch 10 members surrounding said brake-rod, one rotating with the handle and the other connected with the movable part which actuates the brakes, one of said clutch members being movable longitudinally, and a releasing device 15 which moves said movable member longitudinally with relation to said handle when

the handle is rotated to a predetermined position.

9. A brake-operating device, comprising an operating-handle, adapted to rotate but fixed 20 against longitudinal movement, a movable clutch member mounted thereon, a second clutch member connected with a movable part which actuates the brakes, the two said clutch members rotating about the same axis, 25 and a releasing device which releases or disengages the two clutch members when the handle is moved to a predetermined position.

MICHAEL O'BRIEN.
